UNITED STATES PATENT OFFICE.

EDWARD A. BRODTKORB AND AUGUST C. BRODTKORB, OF EDGELEY, NORTH DAKOTA.

CRATE.

Application filed July 9, 1926. Serial No. 121,812.

Our invention relates to crates. While intended more particularly for use as an egg crate, it will be understood that the crate may be used for other purposes. An object 5 of the invention is to provide a strong and durable crate which may be used repeatedly. It is customary to provide crates with covers which are nailed in place. The removal of such covers frequently damages the crate 10 to such an extent that it is not suitable for re-use. A special object, therefore, of our invention is to provide means for securing the cover in place on the crate in such manner that the removal of the cover will not 15 injure the crate including the cover.

The full objects and advantages of our invention will appear in connection with the detailed description thereof, and the novel features of our inventive idea will 20 be particularly pointed out in the claim.

In the accompanying drawings which illustrate our invention in two different forms,—

Fig. 1 is a side elevational view of one 25 form of the device. Fig. 2 is a view thereof in central vertical longitudinal section. Fig. 3 is a top plan view. Fig. 4 is a side elevational view. Fig. 5 is a view in horizontal cross section on the line 5—5 of Fig. 30 2. Fig. 6 is a fragmentary view in section on the line 6—6 of Fig. 2. Fig. 7 is a view of a modified form in central vertical longitudinal section.

Referring to the construction shown in 35 the drawings, and first more particularly to the form shown in Figs. 1 to 6, the numeral 10 designates the two side members of the crate. Each of the two end members of the crate includes a frame which consists of upper and lower bars 12 and 14, two vertical bars 16 and additional upper and lower bars 18 and 20 placed outside of and upon the bars 12 and 14 respectively. The end wall 40 is completed by a sheet metal member having a body portion 22 located inside the frame. This body portion is bent at its two 45 sides to produce outwardly turned flanges 24 and inwardly turned flanges 26 spaced from each other the proper distance to receive the ends of the side members 10 as will 50 be understood from Figs. 1 and 5. The body portion 22 at its lower end is bent to produce an outwardly extending flange 28 and an inwardly extending flange 30 to receive the end of a bottom crate member 32 55 as will be understood from Figs. 2 and 5.

The ends of the flange 30 are preferably turned upwardly as indicated at 34 in Figs. 4 and 5 and the sides and ends are secured in place by nails 36, it being understood 60 that the bottom 32 is similarly secured. The body portion 22 at its upper end is bent to produce an outwardly extending flange 38 and an inwardly extending flange 40 to receive the end of a cover member 42 and the 65 rear end of the flange 40 is preferably turned downwardly and secured as indicated at 44. The front end of the flange 40 is not turned downwardly in order that slideways may be provided which are open 70 at the front. It will, therefore, be apparent from Figs. 1 and 5 that the cover may be slid into place at both of its ends between the flanges 38 and 40. The cover is then held from sliding out by suitable fasteners 75 such as screws 46 shown in Fig. 3, and if desired fasteners with seals 48 may be provided so that the cover cannot be removed without breaking the seals. It is often desirable to provide the crate with a trans- 80 verse vertical partition such as the partition 50. In order to secure the partition, U-shaped metal strips 52 are secured inside the side walls 10 for receiving the ends of the partition. The strips 52 are preferably 85 left with projecting ends 54 which are turned down outside the wall 10 and secured in place. The construction thus far described involves a special construction of 90 crate which is very strong and durable and which may be used over and over since the 95 cover may be readily removed without causing the damage to the crate including the cover which results from removing a cover nailed in place in the usual manner. Fig. 7 shows how the cover feature of our invention may be used with the existing form of 100 crate. Metal strips 56 are secured to the tops of the end members E on the inner side thereof. Each of these strips is bent 105 to produce an outwardly extending flange 58 and an inwardly extending flange 60 thereby forming slideways the same as previously described for receiving the ends of a cover 62 which may be secured in place in 110 the manner previously stated.

We claim:

In a crate, the combination of vertical and horizontal frame members at each of the two ends of the crate, additional upper 110 and lower frame members lying against and outside of the said horizontal frame mem-

bers and overlapping said vertical frame members, rectangular sheet metal members secured to said frame members within the crate, said metal members at their four margins being bent into outwardly and inwardly extending flanges spaced from each other to receive the margins of the sides, bottom, and cover of the crate, the flanges at the top and bottom being longer than the flanges at the sides so as to extend to the

outer surface of said additional upper and lower frame members, means for securing said sides and bottom permanently in place, and means for securing said cover removably in place in order that it may be slid in 15 its receiving flanges.

In testimony whereof we hereunto affix our signatures.

EDWARD A. BRODTKORB.
AUGUST C. BRODTKORB.
